AIRCRAFT

William C. Sleeman, Jr., Newport News, Va., and Thomas A. Toll, Lancaster, Calif., assignors to the United States of America as represented by the Administrator of the National Aeronautics and Space Administration

Continuation of design application Ser. No. 61,939, Aug. 18, 1960. This application May 19, 1961, Ser. No. 65,299

Term of patent 14 years

(Cl. D71—1)

(Granted under Title 35, U.S. Code (1952), sec. 266)

FIG. 1

FIG. 2

FIG. 3

FIG. 4

FIG. 1 is a top perspective view of an aircraft embodying our new design;

FIG. 2 is a side elevation thereof;

FIG. 3 is a bottom perspective view thereof; and,

FIG. 4 is an enlarged rear perspective view of one of the auxiliary wing sections shown in full lines in FIGS. 1, 2, and 3.

The dominant features of this design reside in the auxiliary wing sections shown in full lines on the drawing.

This application is a continuation of our earlier filed application, Serial No. D. 61,939, filed August 18, 1960, now abandoned.

The invention described herein may be manufactured and used by or for the Government of the United States of America for governmental purposes without the payment of any royalties thereon or therefor.

We claim:

The ornamental design for an aircraft, as shown and described.
